BARNEY Y. PERKINS, BURT T. WELLEBORN, AND RICHARD W. STARKE, OF ATLANTA, GEORGIA, ASSIGNEES TO BUTTERS MANUFACTURING COMPANY, OF ATLANTA, GEORGIA, A CORPORATION OF GEORGIA

SOUND RECORD GROOVE FINDER

Application filed June 11, 1930. Serial No. 460,465.

For causing sound and vocal effects in connection with the display of motion pictures gramophone equipment is used in which a table for supporting and operating a sound record is rotated in timed relation to the movement of the film and a tone arm cooperates with the sound record in the usual manner. The record is of the disc type and the needle carried by the tone arm operates in the spiral grooves of the record, such grooves being utilized to move or feed the tone arm across the record.

Heavy vibrations in the building or in the projecting room, such as might be caused by heavily laden trucks passing along the streets, surface or subway cars, or from some other sources common in cities, are apt to jar the needle from the groove in which it normally operates. When this occurs the picture and the sound or vocal effects are out of synchronism and the exhibition, of course, is unintelligible. Heretofore it has been necessary to interrupt the exhibition and start the film and the sound record at the beginning again. This occasions serious loss, delay and dissatisfaction.

The present invention, which may be briefly designated as a sound record groove finder, proposes simple and practical mechanism operated in connection with the record whereby in the event of the sound needle being jarred from the groove in which it normally operates such needle may be restored to the proper groove in a moment or two of time, thereby restoring the exact synchronization of the film and the sound or vocal effects and avoiding all interruption of the exhibition.

In general the invention contemplates an element positively driven in timed relation to the movement of the record and which is caused positively to follow or track with the grooves of the record, which gives a clear and certain indication of the particular groove required for engagement by the sound needle at any moment in order to insure and maintain the synchronization of the film and the sound or vocal effects and which enables the placing of the needle in such groove in a moment or two of time and without any

interruption in the operation of the record or the film.

An embodiment of the invention is illustrated in the accompanying drawings, in which:

Figure 1 is a top plan view showing the groove finder in operative relation to a disc record and tone arm. 55

Figure 2 is a side elevation of the same with parts shown in section. 60

Figure 3 is a sectional view on the line 3—3 of Fig. 1. 65

Figure 4 is a sectional view on the line 4—4 of Fig. 2.

Figure 5 is an end elevation of the groove 65 finder in operative relation to a disc record and tone arm.

Figure 6 is a horizontal sectional view on the line 6—6 of Figure 2.

Figure 7 is a somewhat enlarged sectional 70 view on the line 7—7 of Figure 6.

Figure 8 is a cross sectional view on the line 8—8 of Figure 6.

Figure 9 is a detail sectional view of the means for securing the groove finding 75 pointer.

Figure 10 is a horizontal sectional view on the line 10—10 of Figure 8.

Figure 11 is a sectional view on the line 11—11 of Figure 6. 80

Figure 12 is a detail sectional view of the chuck by which the operating worm is connected to the central post of the record supporting table.

Figure 13 is a detail sectional view on the 85 line 13—13 of Figure 10.

Figure 14 is a detail plan view of the guide-sleeve for the adjusting rod by which the drive of the groove finding needle is controlled. 90

The gramophone equipment herein illustrated is of well known construction and includes the usual table A (Fig. 2) for the support of a record B, the table being driven in timed relation to the film and arranged above a supporting pedestal C upon which is mounted a rotatably adjustable collar D carrying a bracket E which supports the tone arm F, the latter being provided with the 95 100

usual needle G for engagement with the record.

The principal elements of the mechanism of the present invention are mounted in a rectangular frame 1 which is supported over the record and is provided at its outer end with depending lugs 2 (Fig. 2) by which it is pivoted as at 3 to a supporting arm 4. Since the operative relation of the groove finding element to the tone arm must be maintained in any position in which the tone arm may be set with reference to the pedestal C as an axis, the arm 4 is connected to the same element to which the tone arm is connected, that is to say, the rotatably adjustable collar D, the connection of the tone arm to said collar for support thereby being effected by U-bolts 5 in co-operation with a saddle piece 6 at the lower end of the arm 4. The groove finder includes an operating shaft 7 (Fig. 6) having bearings in the end bars of the frame 1. The shaft 7 projects beyond the inner end of said frame and carries at its inner end a gear element 8 by which it is normally driven. For the operation of the groove finder the weight 9 by which the record is pressed against the table A is of special form for co-operation with the gear element 8. As shown and preferred such weight is formed with a peripheral worm 10 for engagement with the element 8, the latter being in the form of a spiral pinion.

In order to provide for the removal and replacement of the record the frame 1 is mounted to be swung laterally as shown in broken lines in Figure 1, thereby to disengage the pinion 8 from the worm 10 and also to be swung upward as indicated in broken lines in Figure 2. The frame 1 is directly connected to a supporting post 11 (Fig. 5) which fits between the lugs 2 and through which the pivot pin 3 extends. The post 11 has a depending journal extension 12 (Fig. 2) which is rotatably fitted in a cylindrical sleeve 13 formed or provided at the upper end of the arm 4. The journal extension 12 rests against a supporting screw 14 threaded through a plate 15 screwed to the lower end of the sleeve 13, a suitable step bearing 16 being provided between the lower end of the journal extension 12 and the screw 14.

The object of supporting the post 11 by the screw 14 is to enable said post, and therewith the groove finder, to be set at an elevation appropriate to the thickness of the particular sound record, such thickness varying in different cases. When such setting has been made the screw 14 is fixed by means of a lock nut 17 which bears against the plate 15.

In order normally to maintain the engagement of the pinion 8 with the worm 10 the arm 4 is provided with a spring loaded plunger 18 (Fig. 4) which projects through an opening in the sleeve 13 and normally presses against a shoulder 19 provided by an angular

recess 20 which is formed in the peripheral surface of the journal extension 12, the recess 20 being of suitable depth to provide for the engagement of the plunger 18 against the shoulder 19 in any position at which the journal extension 12 may be set by the adjustment of the supporting screw 14. The plunger 18 and its loading spring are carried by a cylindrical casing 21 from the inner end of which said plunger projects. The casing 21 is externally threaded and is fitted in a bracket 22 suitably secured to the arm 4, said bracket co-operating with said casing as a nut and the casing being provided at its outer end with a knurled head 23 by which it may be adjusted in order to regulate the tension of the loading spring for the operation of the plunger 18. By virtue of the engagement of the plunger 18 against the shoulder 19 the frame 1 will be normally held in a position wherein the pinion 8 has suitable engagement with the worm 10. When it is desired to remove the record from the table the frame 1 is first swung laterally outward against the pressure opposed by the plunger 18 and said frame is then raised about the pivot 3 to a vertical position in which the normally vertical outer edges of the lugs 2 bear uniformly upon a supporting flange or collar 24 formed or provided at the lower end of the supporting post 11. The frame 1 thereby remains in an upright position, permitting the removal of the record and the positioning of another record on the table A, after which the frame 1 is lowered about the pivot 3 and then swung inward until the pinion 8 engages the worm 10, such engagement being maintained by the plunger 18 as above explained.

The weight 9 is preferably coupled to the post a by which the record is centered upon the table A, such post rotating with the table. For this purpose the weight 9 is provided with a central hollow boss 25 (Figs. 3 and 12) within which is slidably fitted a chuck 26 having spring jaws 27. The jaws 27 tend to spring outward and are formed at their lower ends with external cam surfaces 28 for engagement with conforming cam surfaces 29 formed along the central opening of the boss 25. The chuck 26 is provided with an upwardly extending stem 30 which projects through an opening in a cap 31 secured to the upper end of the boss 25. The chuck is normally pressed downward by a spring 32 arranged within the boss 25 and bearing at its lower end against a collar 33 resting on a shoulder on the chuck and at its upper end against the cap 31. Above the cap the stem 30 is pivoted to a cam 34 having an operating handle 35, the cam having a recess into which the stem 30 projects. The cam 34 bears against the cap 31 and when the handle 35 is pushed down the cam 34 by its reaction against said cap raises the chuck 26 whereby the spring jaws 27 are caused by

the co-operation of the cam surfaces 28 and 29 to engage tightly with and upon the post *a*. In this way the weight 9 is effectively coupled to said post to be driven therefrom.

5 When it is desired to remove a record B from the table A the handle 35 is raised and the spring 32 pushes the chuck 26 downward and effects its disengagement from the post *a*. The frame 1 having been moved to the upright position previously described with resultant disengagement of the pinion 8 from the worm 10, the weight 9 may now be lifted from the record, thus permitting the latter to be removed. When another record has 10 been placed upon the table and centered over the post *a*, the weight 9 is replaced, its chuck 26 being fitted over the post *a* and engaged therewith by moving the handle 35 to its lower position.

15 The groove finding element, to be later described in detail, is moved lengthwise of the frame 1 by a suitable carriage 36. Inasmuch as the number of grooves per inch is different in different makes of records, being 86 per inch in records of certain makes and 92 per inch in records of other makes, provision is made for operating the carriage 36 at a rate which will correspond to the number of grooves per inch of the particular record in use at the time. Accordingly, the operation of the carriage 36 may be derived either from the operating shaft 7 or from a countershaft 37 (Fig. 6). The shafts 7 and 37 are formed within the frame 1 with screw threads 38 and 39, respectively, of appropriate extent, the screw threads of the shaft 7 being of a pitch corresponding to 86 grooves per inch in the sound record and the screw threads of the shaft 37 being of a pitch corresponding to 92 grooves per inch in the sound record. The shaft 37 is driven from the shaft 7 to which it is suitably geared, the gearing (Figs. 6 and 11) being arranged at the outer end of the frame 1 and consisting of spur gears 40 and 41 on the shafts 7 and 37, respectively, and an intermediate spur gear 42 engaging the gears 40 and 41 and mounted on a short shaft 43 which is journaled in and projects beyond the adjacent end bar of the frame 1, the shaft 45 43 having a knurled hand grip 44 for a purpose to be described. The carriage 36 fits transversely over the frame 1 and includes side plates 45 and a top plate 46. The side bars of the frame 1 are formed with external longitudinal grooves 47 preferably of V-cross section and the side plates 45 of the carriage 36 are provided with suitably mounted rollers 48 whose peripheral portions conform to and engage in the grooves 47, the latter thereby 50 functioning as guides for the carriage. The side plates 45 are also formed with rectangular openings 49, in which are set laterally adjustable blocks 50 and 51 (Fig. 8), these being for co-operation respectively with the shafts 7 and 37. The blocks 50 and 51 have a fairly

close fit in the openings 49 and one or the other of said blocks is utilized, in the manner to be described, to effect the movement of the carriage 36, said blocks extending through longitudinal slots 1a in the respective side bars of the frame 1.

The blocks 50 and 51 have their inner faces formed with threads 52 and 53 which extend through arcs not exceeding half circles. The block 50 is for engagement by means of its threads 52 with the shaft 7 and the block 51 is for engagement by means of its threads 53 with shaft 37. The construction is such that when the block 50 is engaged with the shaft 7 the block 51 is disengaged from the shaft 37 and vice versa. In order conveniently to effect this relation the blocks 50 and 51 are secured to the ends of a laterally adjustable transverse bar 54 which is slidably mounted in a sleeve 55 formed with or otherwise provided at the upper side of the plate 46. The bar 54 is provided with a centrally located operating knob 56, the shank of which projects through a slot 57 in the sleeve 55, said slot having at its ends angular extensions 58 and 59 respectively (Fig. 14). The bar 54 is rotatably connected to the blocks 50 and 51 whereby it may be turned about its axis. When the bar 54 is positioned with the shank of its knob 56 in the extension 58 the block 50 is held engaged with the shaft 7 and the block 51 is held disengaged from the shaft 37; and when the bar 54 is positioned with the shank of its knob 56 in the extension 59 the block 51 is held engaged with the shaft 37 and the block 50 is held disengaged from the shaft 7. In this way the carriage 36 may be coupled to either of the shafts 7 or 37 accordingly as rate of movement of said carriage is to be for a record having 86 grooves to the inch or for a record having 92 grooves to the inch.

The frame 1 is preferably formed or provided with a cover plate 60 to protect the threaded shafts 7 and 37 from dust and the gears 40, 41 and 42 are, for a like purpose, preferably enclosed in a casing 61 secured to the adjacent end bar of the frame 1, the hand grip 44 being located externally of the casing 61.

The groove finding element may be of various forms. It is, however, conveniently in the form of a needle-like pointer 62 projecting from a transversely movable slide plate 63 (Figs. 1, 8, 10 and 13) supported by the carriage 36. The slide plate 63 is held in operative relation to said carriage and is also guided in its transverse movement by rollers 64 mounted on stems 65 secured to and projecting below the plates 45 at the ends thereof, the rollers 64 having peripheral portions of V-shaped cross section which engage conformably in V-shaped grooves 65a formed in the side edges of the slide plate 63. The shank of the pointer 62 is inserted through a diametrical opening 66 in a screw 67 having

a lower head 68 adjoining the opening 66. The screw 67 projects through an opening in said slide plate and at the upper side of said slide plate carries a clamping nut 69 by which 5 the head 68 may be drawn tightly against the under side of the slide plate 63 to secure the pointer 62. It is obvious that by this arrangement the pointer 62 may also be set to project at any angle which may be desired or 10 which may be required in a particular case.

It is necessary to the satisfactory operation and use of the pointer 62 for its intended purpose that said pointer in its movement over the record follow an arc taken from the axis 15 of the tone arm and hence concentric to the arc followed by the sound needle. For this purpose a horizontal plate 70 is suitably supported from and below the frame 1, as by attachment at one end to a post 73 carried by 20 and projecting laterally from one of the lugs 2, the plate 63 being arranged between the plate 70 and said frame. The plate 70 projects at one side beyond the frame 1 and is formed with a slot 71 of an extent to encompass 25 all of the record surfaces in connection with which the groove finder may be employed. The slot 71 is of such curvature and the plate 70 is so positioned that said slot is concentric to the arc described by the sound 30 needle in its movement across the record. The slide plate 63 is provided on its lower side with a guide pin or roller 72 which is located in and peripherally engages the sides of the slot 71. It follows that as the carriage 35 36 moves along the frame 1 in consequence of its operation by either of the shafts 7 or 37 the position of the slide plate 63 will be progressively altered by the slot 71 which acts on the slide plate 63 through the guide piece 40 72. In this way the movement of the pointer 62 is caused to conform to the arc described by the sound needle in its movement across the surface of the record.

The carriage 36 is initially positioned to 45 set the pointer 62 over the first sound groove of the record and for such initial position of said carriage provision is made for its manual adjustment by a free sliding movement along the frame 1 and also for its adjustment by a 50 manual operation of either the shaft 7 or 37 as the case may be, the free movement of the carriage along the frame providing a coarse adjustment and the movement of the carriage by the manual operation of either of the shafts 55 7 or 37 providing a fine adjustment.

To enable the fine adjustment of the carriage 36 it is necessary that the shaft 7 be disconnected, operatively, from the pinion 8. For this purpose said pinion is loosely 60 mounted on the end of said shaft and has its hub formed for engaging cooperation with a friction clutch element 74 (Figs. 6 and 7) slidably keyed to said shaft. The clutch member 74 is formed with an axial hub-like 65 extension sleeve 75 in which is arranged a

spring 76 for pressing the clutch member 74 into engagement with the hub of the pinion 8. The spring 76 bears at its end remote from the clutch element 74 against a collar 77 secured to the shaft 7. The adjacent end 70 of the sleeve 75 is provided with an annular shoulder 78. For effecting the engagement or disengagement of the clutch element 74 relatively to the hub of the pinion 8 a short vertical adjusting shaft 79 is preferably employed. The shaft 79 is journalled in a bracket 80 secured upon the adjacent end of the frame 1 and is provided at its lower end with a depending eccentric pin 81 which engages against the shoulder 78 and at its upper 80 end with a knurled finger piece 82.

When it is desired to effect the coarse adjustment of the pointer 62 the knob 56 is brought to a middle position in the slot 57 (Fig. 14) and thereby moves the bar 54 to 85 a position in which the blocks 50 and 51 are both disengaged from their companion shafts 7 and 37. At such time the carriage 36 may be freely slid along the frame 1 to a position in which the pointer 62 is close to the 90 first sound groove of the record. In order to secure the required exactness in the initial position of the pointer 62 the knob 56 is now operated to engage either of the blocks 50 and 51 with the corresponding shaft 7 or 37 95 as the case may be and the clutch element 74 is disengaged from the hub of the pinion 8 by the manipulation of the shaft 79. At such time the shaft 7 will run free of the pinion 8. By means of the hand grip 44 the gear 42 100 is turned in the appropriate direction and through the gears 40 and 41 operates the shafts 7 and 37, one of which, according to its engagement by corresponding block 50 or 51, will effect the movement of the carriage 105 and thus carry out the fine adjustment required for the accurate positioning of the pointer 62. When such fine adjustment has been completed the shaft 79 is manipulated 110 to re-engage the clutch element 74 with the pinion 8, thereby to cause the shaft 7 to be driven by said pinion with resultant movement of the carriage 36 and pointer 62 in timed relation to the record.

Sound records intended for use in connection with motion picture projecting machines are provided with one or more blank grooves by which the sound needle is brought to the starting point and these "starting" grooves may either be of the same pitch as the sound 115 grooves or of greater pitch. In any case, the number of starting grooves is marked on the record or otherwise made known to the operator and the starting point, that is to say the point at which the sound grooves commence is definitely marked on the record, usually by means of an arrow which is shown in Fig. 1 at b. Assuming, then, that the record herein shown has one complete starting 120 groove, the sound needle is placed in such 125 position as to engage the starting groove.

groove at the point where it begins and the record is turned through a substantially full revolution until the arrow *b* points exactly to the sound needle at which time the movement of the record is stopped. The pointer 62 is thereupon set at a position in which its end is directly over the first sound groove and in close juxtaposition to the sound needle. Such setting of the pointer 62 is obtained by means 5 of the above described coarse and fine adjustments of the carriage 36. To promote convenience in thus setting the pointer 62 a magnifying lens may be employed, said lens being fitted in a holder 83 having a sight opening 84 and the lens holder being pivotally mounted as at 85 upon the upper end of an upright post 86 carried by the slide plate 63. By reason of its pivotal mounting the lens holder may be swung horizontally to any position required, in accordance with the particular angle at which the pointer 62 may project, for enabling the end of said pointer 10 to be viewed through the sight opening 84.

The pointer 62 having thus been initially 25 set with its end substantially coinciding with the starting point of the sound grooves of the record and lying directly over the first sound groove at a point close to the sound needle and very slightly in advance of the engraved 30 surface of said groove, the equipment is now ready for use. In the playing of the record the pointer 62 will move across the sound grooves in exactly timed relation to the movement of the record and its movement will also 35 be in an arc which will conform exactly to the arc of the sound needle as taken from the pivot of the tone arm. So long as the sound needle operates in the proper groove the 40 pointer 62 will at all times exactly track with said needle. If, however, the sound needle should be jarred from its proper or normal groove to one side or the other the pointer 62 will continue to track with the grooves of the 45 record in timed relation to the movement of the record and hence it will be available visually to indicate the particular groove at which the music or vocal effects of the record will synchronize with the film. Therefore, 50 when the sound needle is jarred from its proper operating position it may be almost instantly restored to proper operating position by placing it in the groove with which 55 the pointer 62 tracks, such placement of the sound needle being facilitated by viewing the end of the pointer 62 and the corresponding groove of the record through the sight opening 84. Thus viewing the end of the pointer 60 62 and the corresponding record groove through said sight opening, the sound needle may be quickly and certainly placed in such groove and the synchronization of the music or vocal effects of the record with the film, 65 interrupted by the dislodgement of the sound

needle, restored with ease and certainty in a moment or two of time.

The pointer 62 is to be understood as simply one of a number of available mediums or devices for indicating the particular sound groove in which the sound needle is to operate at any moment during the operation of the record. It will be understood that various other mechanical devices which will serve the purposes in view may be employed. 70 75

Having fully described our invention, we claim:

1. The combination of a sound record disk provided with the usual sound grooves, a rotatable table upon which said disk rests and a tone arm having a sound needle operating in said grooves, of a carriage provided with a groove finding element, a support upon which the carriage is mounted for movement across the disk, mechanism for moving the carriage in timed relation to the movement of the disk and means for causing the groove finding element in its movement with the carriage to follow a path concentric to the path of the sound needle across the disk, said 80 groove finding element being operative to indicate at any moment of the operation of the record the groove required to be engaged by the sound needle in order that the playing of the record at any moment may be in 85 the order of normal sequence. 90

2. The combination of a sound record disk provided with the usual sound grooves, a rotatable table upon which said disk rests, and a tone arm having a sound needle operating 100 in said grooves, of a carriage provided with a groove finding element in the form of a pointer overlying the grooved surface of the record and terminating in proximity to said needle during the operation of the record, a support upon which the carriage is mounted for movement across the disk, mechanism for moving the carriage in timed relation to the movement of the disk and means for causing the groove finding element in its movement 105 with the carriage to follow a path concentric to the path of the sound needle across the disk, said groove finding element being operative to indicate at any moment of the operation of the record the groove required to be 110 engaged by the sound needle in order that the playing of the record at any moment may be in 115 the order of normal sequence. 120

3. The combination of a sound record disk provided with the usual sound grooves, a rotatable table upon which said disk rests, a tone arm having a sound needle operating in said grooves and a body supported centrally on said disk and rotated therewith, of a carriage provided with a groove finding element, a support upon which the carriage is mounted for movement across the disk, mechanism for moving the carriage in timed relation to the movement of the disk and including a gear element, a co-operating gear ele- 125 130

ment engaging with said first gear element and provided upon said body, and means for causing the groove finding element in its movement with the carriage to follow a path concentric to the path of the sound needle across the disk, said groove finding element being operative to indicate at any moment of the operation of the record the groove required to be engaged by the sound needle in order that the playing of the record at any moment may be in the order of normal sequence.

4. The combination of a sound record disk provided with the usual sound grooves, a rotatable table upon which said disk rests, a tone arm having a sound needle operating in said grooves and a body supported centrally on said disk and rotated therewith, of a carriage provided with a groove finding element, a support upon which the carriage is mounted for movement across the disk, mechanism for moving the carriage in timed relation to the movement of the disk and including a gear element, a co-operating gear element engaging with said first gear element and provided upon said body, means for causing the groove finding element in its movement with the carriage to follow a path concentric to the path of the sound needle across the disk, said groove finding element being operative to indicate at any moment of the operation of the record the groove required to be engaged by the sound needle in order that the playing of the record at any moment may be in the order of normal sequence, a bracket upon which the carriage support is mounted for horizontal swinging movement and normally acting yieldable means for urging the carriage support to a position in which

40 said first named gear element engages said second named gear element, said carriage support being movable against the influence of said yieldable means to effect the disengagement of said gear elements.

45 5. The combination of a sound record disk provided with the usual sound grooves, a rotatable table upon which the disk rests, a tone arm having a sound needle operating in said groove and a body supported centrally on said disk and rotated therewith, of a carriage provided with a groove finding element, a support upon which the carriage is mounted for movement across the disk, mechanism for moving the carriage in timed relation to the movement of the disk and including a gear element, a co-operating gear element engaging with said first gear element and provided upon said body, means for causing the groove finding element in its movement with the carriage to follow a path concentric to the path of the sound needle across the disk, said groove finding element being operative to indicate at any moment of the operation of the record the groove required to be engaged by the sound needle in order that the playing

of the record at any moment may be in the order of normal sequence, the carriage support being movably mounted and means normally operative to hold the carriage support in a position in which said gear elements are engaged, said means being operative to permit the movement of the carriage support to effect the disengagement of said gear elements.

6. The combination of a sound record disk provided with the usual sound grooves, a rotatable table upon which said disk rests, and a tone arm having a sound needle operating in said grooves, of a carriage provided with a groove finding element, a support upon which the carriage is mounted for movement across the disk, mechanism for moving the carriage in timed relation to the movement of the disk, means operable at will for disconnecting the carriage from said mechanism whereby the carriage may be moved manually across the disk, and means for causing the groove finding element in its movement with the carriage to follow a path concentric to the path of the sound needle across the disk, said groove finding element being operative to indicate at any moment of the operation of the record the groove to be engaged by the sound needle in order that the playing of the record at any moment may be in the order of normal sequence.

7. The combination of a sound record disk provided with the usual sound grooves, a rotatable table upon which said disk rests, a tone arm having a sound needle operating in said grooves and a body supported centrally on said disk and rotated therewith, of a carriage provided with a groove finding element, a support upon which the carriage is mounted for movement across the disk, mechanism for moving the carriage in timed relation to the movement of the disk and including an operating shaft journalled in the carriage support and provided with a gear element, a co-operating gear element engaging with said first gear element and provided upon said body, said first gear element being loose on said shaft, manually operated clutch means for connecting or disconnecting said shaft relative to said first gear element, and manually operated means for operating said shaft when said first gear element is in disconnected relation to said shaft.

8. The combination of a sound record disk provided with the usual sound grooves, a rotatable table upon which said disk rests, a tone arm having a sound needle operating in said groove and a body supported centrally on said disk and rotated therewith, of a carriage provided with a groove finding element, a support upon which the carriage is mounted for movement across the disk, mechanism for moving the carriage in timed relation to the movement of the disk and including an operating shaft journalled in the

carriage support and provided with a gear element, a co-operating gear element engaging with said first gear element and provided upon said body, said first gear element being loose on said shaft, manually operated clutch means for connecting or disconnecting said shaft relative to said first gear element, manually operated means for operating said shaft when said first gear element is in disconnected relation to said shaft, and means operable at will for disconnecting the carriage from said mechanism whereby the carriage may be moved manually across the disk.

9. The combination of a sound record disk provided with the usual sound grooves, a rotatable table upon which said disk rests and a tone arm having a sound needle operating in said grooves, of a carriage provided with a groove finding element, a support upon which the carriage is mounted for movement across the disk, mechanism for moving the carriage in timed relation to the movement of the disk and means for causing the groove finding element in its movement with the carriage to follow a path uniformly spaced at all points from the path of the sound needle across the disk, said groove finding element being operative to indicate at any moment of the operation of the record the groove required to be engaged by the sound needle in order that the playing of the record at any moment may be in the order of normal sequence.

10. The combination of a sound record disk provided with the usual sound grooves, a rotatable table upon which said disk rests, and a tone arm having a sound needle operating in said grooves, of a carriage provided with a groove finding element, a support upon which the carriage is mounted for movement across the disk, mechanism for moving the carriage in timed relation to the movement of the disk and including two shafts adapted to move the carriage at different rates of speed, and means operable at will for connecting the carriage to one or the other of said shafts.

11. The combination of a sound record disk provided with the usual sound grooves, a rotatable table upon which said disk rests, and a tone arm having a sound needle operating in said grooves, of a carriage provided with a groove finding element, a support upon which the carriage is mounted for movement across the disk, mechanism for moving the carriage in timed relation to the movement of the disk and including two intergeared shafts adapted to move the carriage at different rates of speed, means operable at will for connecting the carriage to one or the other of said shafts and driving means acting on one of said shafts.

12. The combination of a sound record disk provided with the usual sound grooves, a rotatable table upon which said disk rests, and a tone arm having a sound needle operating

in said grooves, of a carriage provided with a groove finding element, a support upon which the carriage is mounted for movement across the disk, mechanism for moving the carriage in timed relation to the movement of the disk and including two intergeared shafts adapted to move the carriage at different rates of speed, means operable at will for connecting the carriage to one or the other of said shafts, driving means acting on one of said shafts, means operable at will for disconnecting said last named shaft from its driving means, and means for manually operating said shafts.

13. The combination of a sound record disk provided with the usual sound grooves, a rotatable table upon which said disk rests, and a tone arm having a sound needle operating in said grooves, of a carriage provided with a groove finding element, a support upon which the carriage is mounted for movement across the disk, mechanism for moving the carriage in timed relation to the movement of the disk and including two intergeared shafts adapted to move the carriage at different rates of speed, means operable at will for connecting the carriage to one or the other of said shafts, driving means acting on one of said shafts and means operable at will for disconnecting the carriage from said mechanism and permitting its manual movement across the disk.

14. The combination of a sound record disk provided with the usual sound grooves, a rotatable table upon which said disk rests, and a tone arm having a sound needle operating in said grooves, of a carriage provided with a groove finding element, a support upon which the carriage is mounted for movement across the disk, mechanism for moving the carriage in timed relation to the movement of the disk and including two intergeared shafts adapted to move the carriage at different rates of speed, means operable at will for connecting the carriage to one or the other of said shafts, driving means acting on one of said shafts, means operable at will for disconnecting said last named shaft from its driving means, means for manually operating said shafts and means operable at will for disconnecting the carriage from said mechanism and permitting its manual movement across the disk.

15. The combination of a sound record disk provided with the usual sound grooves, a rotatable table upon which said disk rests, and a tone arm having a sound needle operating in said grooves, of a carriage provided with a groove finding element, a support upon which the carriage is mounted for movement across the disk and mechanism for moving the carriage in timed relation to the movement of the disk.

16. The combination of a sound record disk provided with the usual sound grooves, a rotatable table upon which said disk rests, and a tone arm having a sound needle operating in said grooves, of a carriage provided with

21. The combination of a sound record disk provided with the usual sound grooves, a rotatable table upon which said disk rests, a tone arm having a sound needle operating in said grooves and a body supported centrally on said disk and rotated therewith, of a carriage provided with a groove finding element, a support upon which the carriage is mounted for movement across the disk, mechanism for moving the carriage in timed relation to the movement of the disk and including a gear element, a co-operating gear element engaging with said first gear element and provided upon said body, means for causing the groove finding element in its movement with the carriage to follow a path concentric to the path of the sound needle across the disk, said groove finding element being operative to indicate at any moment of the operation of the record the groove required to be engaged by the sound needle in order that the playing of the record at any moment may be in the order of normal sequence, a bracket upon which the carriage support is mounted for horizontal and vertical swinging movement and normally acting yieldable means for urging the carriage support to a position in which said first named gear element engages said second named gear element, said carriage support being movable against the influence of said yieldable means to effect the disengagement of said gear elements. 70
17. The combination of a sound record disk provided with the usual sound grooves, a rotatable table upon which said disk rests, and a tone arm having a sound needle operating in said grooves, of a carriage provided with a groove finding element, a support upon which the carriage is mounted for movement across the disk, mechanism for moving the carriage in timed relation to the movement of the disk, means for operating said mechanism from said table, means for disconnecting said mechanism from said operating means and means for manually operating said mechanism. 75
18. The combination of a sound record disk provided with the usual sound grooves, a rotatable table upon which said disk rests, and a tone arm having a sound needle operating in said grooves, of a carriage provided with a groove finding element, a support upon which the carriage is mounted for movement across the disk, mechanism for moving the carriage in timed relation to the movement of the disk and means operable at will for connecting or disconnecting the carriage relatively to said mechanism, the carriage when disconnected being manually movable across the disk. 80
19. The combination of a sound record disk provided with the usual sound grooves, a rotatable table upon which said disk rests, and a tone arm having a sound needle operating in said grooves, of a carriage, a support upon which the carriage is mounted for movement across the disk, mechanism for moving the carriage in timed relation to the movement of the disk, a transversely slideable plate mounted on the carriage and provided with a groove finding element, a stationary plate having a slot curved concentrically to the path of the sound needle in its movement across the disk and a guide piece carried by said slideable plate and engaging in said slot. 85
20. In combination, a sound record disk having the usual sound grooves, a rotatable table upon which the disk rests, a tone arm having a sound needle operating in said grooves, a movable groove finding element, means to direct said element across the disk and means to operate said element from said table including means for timing the movement of said element to correspond to the rotation of the disk whereby said element is operative to indicate at any moment of the operation of the record the groove to be engaged by the sound needle in order that the playing of the record at any moment may be in the order of normal sequence. 90
21. The combination of a sound record disk provided with the usual sound grooves, a rotatable table upon which said disk rests, a tone arm having a sound needle operating in said grooves and a body supported centrally on said disk and rotated therewith, of a carriage provided with a groove finding element, a support upon which the carriage is mounted for movement across the disk, mechanism for moving the carriage in timed relation to the movement of the disk and including a gear element, a co-operating gear element engaging with said first gear element and provided upon said body, means for causing the groove finding element in its movement with the carriage to follow a path concentric to the path of the sound needle across the disk, said groove finding element being operative to indicate at any moment of the operation of the record the groove required to be engaged by the sound needle in order that the playing of the record at any moment may be in the order of normal sequence, a bracket upon which the carriage support is mounted for horizontal and vertical swinging movement and normally acting yieldable means for urging the carriage support to a position in which said first named gear element engages said second named gear element, said carriage support being movable against the influence of said yieldable means to effect the disengagement of said gear elements. 95
